GOLF CLUB HEAD

Fred L. Hoffmeister, Oak Park, Ill.

Application March 19, 1956, Serial No. 40,676

Term of patent 14 years

(Cl. D34—5)

Fig. 1 is a perspective view of a golf club head, showing my new design;

Fig. 2 is a front elevational view thereof;

Fig. 3 is a top plan view thereof;

Fig. 4 is a rear elevational view thereof; and

Fig. 5 is a side elevational view thereof.

I claim:

The ornamental design for a golf club head, substantially as shown.
